UNITED STATES PATENT OFFICE

JAMES A. HEINTZELMAN, OF SUNBURY, PENNSYLVANIA

ELECTRICALLY HEATED SOLDERING IRON

Application filed November 21, 1929. Serial No. 408,815.

The present invention relates to electrical-
ly heated tools and has for its general object
the provision of simple, reliable and eco-
nomical means for electrically heating tools.

5 More specifically my invention relates to
electrically heating soldering irons, wherein
a novel structure is incorporated in the tool
so as to be capable of convenient and easy
operation and the tool embodying a struc-
10 ture wherein the parts may be easily and
quickly assembled and disassembled with re-
spect to one another.

With the above and numerous other ob-
jects in view, as will appear as the descrip-
15 tion proceeds, the invention resides in cer-
tain novel features of construction, and in
the combination and arrangement of parts
as will be hereinafter more fully described
and claimed.

20 In the drawings:

Figure 1 is an elevation of the soldering
iron embodying the features of my inven-
tion,

Figure 2 is an enlarged longitudinal sec-
25 tion taken substantially on the line 2—2 of
Figure 1,

Figure 3 is a transverse section taken sub-
stantially on the line 3—3 of Figure 2,

Figure 4 is a perspective view of the hol-
30 low stem,

Figure 5 is a perspective view of the mov-
able contact arm, and

Figure 6 is a diagrammatic view for il-
lustrating the use of the soldering iron.

35 Referring to the drawings in detail, it will
be seen that the numeral 5 denotes a hollow
handle of insulating material having a slot
6 formed in one side thereof adjacent the
forward end thereof.

40 In said forward end of the handle 5 there
is a bushing 7 of electrical conducting ma-
terial to receive one end of a hollow stem 8
also of electrically conducting material and
having its outer end enlarged in diameter
45 as indicated at 9 to receive a carbon 10. The
hollow stem 8 has a covering 8' of insulating
material thereon as shown to advantage in
Figures 1 and 2. A plug 11 has fixed to one
end thereof a disk 12 from the periphery of
50 which extends laterally a spring contact arm

14 having a curved terminal 15 adjacent
which projects from the arm 14 a shank 16
terminating in a head 17.

The plug 11 is partially inserted in the
other end of the handle 5 held in place by
means of a screw 18 so that the spring arm
14 extends longitudinally of the handle rest-
ing in a groove 19 formed interiorly thereof
and having the contact 15 terminating in the
slot 6 a distance from the bushing 7. 60

The conductor, such as a wire or the like
21, is secured to an intermediate portion of
the arm 14 and extends through a central
opening in the disk 12 and thence outwardly
of the handle through a bore in the center of
the plug 11. The outer end of the wire has a
spring clip 22 attached thereto for connecting
to one terminal of a battery which we will
presume is grounded. 65

Desiring to solder the element 24 to the
70 frame 25 which is grounded it will be seen
that by placing the carbon 10 into engage-
ment with the frame 25 and the element 24
and depressing the head 17 to force the con-
tact 15 in engagement with the bushing 7 that
75 the circuit will be closed thereby setting up
sufficient heat at the carbon for soldering
purposes.

It is thought that the construction, utility
and advantages of this invention will now
80 be quite apparent without a more detailed
description thereof.

The present embodiment of the invention
has been described in considerable detail
merely for the purposes of exemplification
85 since in actual practice it attains the features
of advantage enumerated as desirable in the
statement of the invention and the above
description.

It will be apparent that changes in the
90 details of construction, and in the combina-
tion and arrangement of parts may be re-
sorted to without departing from the spirit
or scope of the invention as hereinafter
claimed or sacrificing any of its advantages. 95

Having thus described my invention, what
I claim as new is:

A device of the class described comprising
a hollow insulator handle having a bush-
ing in one end thereof, a plug in the other 100

end thereof, a disk on the inner face of the plug, a spring switch arm extending from the disk so that its terminal is normally spaced from the bushing, a circuit wire extended through the plug and connected to said arm and a depressible button secured to the arm and projecting through a slot in the handle so that the arm may be flexed to engage the terminal with the bushing.

10 In testimony whereof I affix my signature.
JAMES A. HEINTZELMAN.
